His Attorneys.

UNITED STATES PATENT OFFICE

ANDREW J. GALLAHER, OF ST. LOUIS, MISSOURI

PLUG FOR OIL WELLS AND APPARATUS FOR SEATING THE SAME

Application filed April 17, 1930. Serial No. 444,912.

This invention relates to means for closing oil wells and more particularly those wells in which great pressures exist and which cannot be closed by ordinary methods.

5 One of the objects of this invention is to provide a plug with apparatus to be used for placing it which will be effective in closing oil wells where large pressures exist.

Another object of the invention is to provide a plug for oil wells with apparatus for placing it adapted to utilize the pressure of the well to assist in positioning the plug.

Other objects will be apparent from the following detail description taken in connection with the accompanying drawings in which:—

Fig. 1 is a view partly in section showing the device in connection with a casing after the first step has been taken toward placing 20 the plug.

Fig. 2 is a view similar to Fig. 1 but with the plug in position.

Fig. 3 is a view partly in section showing the plug in position and after the removal 25 of the apparatus for placing it.

Fig. 4 is a view partly in section illustrating means and method for removal of the plug.

Fig. 5 is a cross-section through the plug 30 element.

A plug 1 comprises a solid metallic piece having a bore 2 therethrough from its point to its upper end and having external threads 3 at its upper end to engage internal threads 35 at the upper end of a nipple 4. A coupling 5 has internal threads on each end adapted to connect the nipple 4 to the well casing 6.

A member 7 is secured to the upper end 40 of the nipple 4. The member 7 is a shell having an end wall 8 which forms a chamber communicating with the bore 2. Its outer surface is cylindrical in form and is adapted to telescope inside a cylindrical member 9, forming with the member 9 a piston within 45 a cylinder. The end wall 8 has an orifice 10 communicating with the interior of the cylinder 9. The cylinder 9 has an end wall 11 in which is secured a pipe 12 controlled by a valve 13.

50 A collar 14 is secured about the casing and

carries pawls 15 adapted to grasp the casing and prevent the displacement of the collar 14. Lugs 16 are carried by the collar 14 and lugs 17 are carried by the cylindrical member 9. Cables 18 of equal length are attached at one 55 end to a lug 16 and at the other end to a lug 17.

In operation of the device the assembly just described is made with the casing. The point of the plug 1 is inserted in the head of 60 the casing, as shown in Fig. 1. The pressure from the well passes through the bore 2, through the orifice 10, and into the chamber formed by the cooperation of the elements 7 and 9. The pressure within the chamber 65 has the tendency both to upend the device to a vertical position and to force the piston member 7 downward, thus forcing the plug into the casing. The coupling 5 is then screwed into the casing 6, as shown in Fig. 70 2. In the preceding operation thus described, the valve 13 may be closed or partly closed, depending upon the well pressure.

After the coupling 5 has been secured to the casing the valve 13 may be opened and 75 the member 7 removed from the nipple 4. The plug will then be in the condition shown in Fig. 3, the well flowing through the bore 2. A gate valve 19 may be secured to the nipple 4 whereby the flow of the well may be 80 controlled as desired.

The plug 1 may be provided with spiral grooves 20 whereby the contents of the well flowing against the plug will cause it to spin and thereby assist in placing the plug and 85 screwing the coupling 5 to the casing 6.

An angular socket 21 is provided in the upper end of the plug 1 and is adapted to be engaged by a tool such as a wheel-wrench 22, as shown in Fig. 4. After the plug is in position and the well has been flowing for some time, the well pressure may be so decreased as to make it desirable to remove the plug. In that case the wrench 22 operating in the socket 21 may be used to unscrew the plug 95 from the nipple so that it may be removed through the valve 19.

While this device has been described in connection with plugging the casing of an oil well it is obvious that it may be applied 100

to closing any conduit which carries fluids under pressure.

It is also obvious that various changes may be made in the details of construction within 5 the scope of the appended claims without departing from the spirit of this invention.

I claim:

1. A device of the class described comprising a conical plug having a passage there- 10 through, a fitting adapted to secure the plug to a well casing when in position, and means operable by the pressure of the well to assist in forcing the plug to position.

2. A device of the class described com- 15 prising a conical plug having a passage there- through, a fitting adapted to secure the plug to the well casing when in position, a piston and cylinder operable by the well pressure communicated through said passageway to 20 the cylinder, and arranged and adapted to assist in forcing the plug to position.

3. A device of the class described comprising a conical plug having a passage there- through, a fitting adapted to secure the plug 25 to a well casing when in position, a member secured to the plug, a second member teles- coping said first member and forming a pres- sure chamber therewith, means for securing the second member to the well casing, and 30 means whereby the pressure of the well may be communicated through said passage to said chamber.

4. A device of the class described com- 35 prising a conical plug having a passage there- through, a fitting adapted to secure the plug to a well casing when in position, means operable by the pressure of the well to assist in forcing the plug to position, and means ex- ternal of the plug whereby the pressure of the 40 well will exert a spinning movement to said plug.

5. A device of the class described comprising a conical plug having a passage there- through, a nipple secured by a threaded con- 45 nection about the plug, a fitting adapted to secure the nipple to a well casing, a gate valve adapted to be secured to the upper end of said nipple, and means on the upper end of the plug adapted to be engaged by a tool pass- 50 ing through said valve for the removal of the plug from the nipple.

6. A device of the class described comprising a conical plug having a passage there- through, a fitting adapted to secure the plug 55 to a well casing when in position, a hollow piston member secured to said plug, a cylin- drical member having a closed upper end and positioned about said piston member, means for securing the cylindrical member to the 60 well casing, and means for communicating the well pressure through said passage in the plug to the cylindrical member.

ANDREW J. GALLAHER.
